BOW STRAIGHTENING APPARATUS

Frank J. Stevens, Providence, R. I., assignor to
 Cranston Print Works Company, Cranston,
 R. I., a corporation of Rhode Island

Application August 12, 1936, Serial No. 95,524

8 Claims. (Cl. 26—52)

This invention relates to bow straightening apparatus. It is herein particularly shown and described in its application to a tentering machine but this is merely illustrative because it 5 may be used with any continuously moving strip of cloth.

In the weaving of fabric the threads of the woof, called filling threads, are laid or woven straight across the warp and it is important 10 that they remain so throughout the subsequent processing of the goods. It is readily appreciated that if these cross threads are laid straight to form a desired pattern and later become curved, called in the art "bowing", serious and 15 damaging deformity of the pattern results. Likewise with plain cloth which is to be printed with some design, if the filling threads are not straight across when the piece is printed it is well-nigh ruinous to the design if straightening 20 of the bowing is later attempted. And even where the cloth is not woven or printed with any 25 figurative design, being simply plain goods, it is nevertheless highly desirable to have no bowing not only as a matter of appearance but because when the goods are finally cut to a pattern bowing leads to unexpected distortion of the cloth when it is eventually made up into a garment.

It is an object of this invention to provide 30 means to straighten the bowing of the filling threads. Cloth is woven into long strips or pieces which, during the subsequent processing, are temporarily stitched together so that the fabric may continue to be fed as a strip indefinitely. Generally speaking whenever such a continuous 35 strip is being fed it is possible for the bowing to occur, but it almost invariably occurs while the cloth is passing through a tentering machine. Accordingly the present invention may be employed particularly with a tentering machine, and 40 such use is herein disclosed as the best mode in which I have contemplated applying the principles of my invention. As previously noted, this showing is to be taken as merely illustrative for it is intended that the patent shall cover by 45 suitable expression in the appended claims whatever features of patentable novelty exist in the invention as a whole.

Figure 1 is a plan view of several sections of a 50 strip of fabric, showing somewhat diagrammatically how the bowing may occur;

Figure 2 is a side elevation of the head or delivery end of tentering machine to which my device has been applied;

Figure 3 is a similar elevation of the same, 55 partly in section as on line 3—3 of Figure 6;

Figure 4 is a side elevation, as in section on line 4—4 of Figure 6, through the novel feeding rolls;

Figure 5 is a plan view; and

Figure 6 is a front elevation taken as on line 5—6 of Figure 2.

Referring now more particularly to the drawings and especially to Figure 1, it is highly desirable for the woven fabric to remain as indicated at A with the woof or filling threads B straight 10 across the warp threads C. Unfortunately this desired condition is seldom realized and more often than not the woof threads become curved as shown at B1 and at B2. As previously stated the present invention is directed to the straightening of such bowing, whether the filling threads be curved as at B1, or reversely curved as at B2.

A tentering machine affords a most desirable place in the processing of cloth for the employment of my invention. In a tenter the cloth is 20 stretched sidewise promptly after entering the machine and thereafter travels a considerable distance with the selvage engaged by the traveling clips of the machine. The drawings show the head or delivery end of a tenter with my improved bow eliminating means applied thereto. The head end comprises side frame members 1 and 2 carrying a main drive shaft 3 which may be driven from any suitable source of power. Splined to this shaft, and movable therewith, 30 are beveled pinions 4 and 5. Each pinion meshes with a beveled gear 6, 7, attached to the lower end of a vertical shaft 8, 9, to the upper end of which is secured a sprocket gear 10, 11. Each sprocket gear drives an endless chain 12, 13 indicated by the dot-and-dash lines in Figure 5. This chain comprises a series of clips 14, shown in Figure 6, those of one chain gripping one side of the cloth strip A while the clips of the other chain grip the other side of the strip. The 40 chains extend for a considerable longitudinal distance, being guided by chain rails 16, 17 from the cloth receiving end to the delivery or head end of the tenter. As a chain reaches its sprocket gear the clips are engaged by an opening flange 18, 19 and caused to open, thereby permitting the cloth to continue forward as the chain reverses its direction of travel. The stretched cloth passes over a bar 20 to a winder (not shown) 50 where it is wound on itself into a roll.

All of the apparatus thus far described is old in the art and is merely representative of any tenter, herein disclosed as indicating broadly any means for feeding the edges of a piece of cloth. The novel apparatus will now be described,

by means of which apparatus any bowing of the filling threads may be straightened and the cloth delivered to the winder with these threads positioned straight across the strip.

5 Secured to the side frames 1 and 2 are standards 21, 22 carrying an axle rod 23 to which is secured arms 25, 26 between which is rotatably supported a roll 27. These arms are so positioned on the rod 23 that the center of the roll 27 will be substantially over the center line of the fabric piece A, whose edges are indicated by dotted lines a, a' in Figure 5. Beneath the cloth is another roll 28 rotatably supported by arms 29, 30 on standards 31, 32. The shaft 33 of this lower roll 28 carries a sprocket gear 34 which is connected by chain 35 to a variable speed control device 36 of any suitable design which may, for example, be driven by another chain 37 running between gear 38 and a sprocket gear 39 on the main drive shaft 3. Obviously the speed of chain 35, gear 34 and roll 28 may be different from that of gear 38 as determined by the setting of the variable speed controller 36. The hand-wheel 40 is representative of any suitable means for determining the setting of the device 36 and the speed of roll 28.

At one end of the rod 23 is secured an arm 41 which is connected by an extended link 42 with a chain or cable 43 running through a housing 44 and around a guide wheel 45 to a vertical shaft 46. The latter is provided with external threads which are engaged by a hand-wheel nut 47 at the upper end of a suitable support 48. By turning this hand-wheel, shaft 46 may be raised or lowered and, by means of chain 43 and link 42, the arm 41 may be turned. This will cause the axle rod 23 and arms 25, 26 to likewise turn and either press roll 27 toward roll 28 or move the rolls apart. Secured to arm 41 is a spring member 49 so arranged as to constantly urge arm 41 upward, thus imposing a tension on the chain 43.

While it is to be understood that both roll 27 and 28 may be cylindrical rolls, I prefer that one of them shall be non-cylindrical as shown. As illustrated, roll 27 is not a true cylinder but has its greatest diameter at the middle and its smallest diameters at the ends. Between these extremes of diameter the variation may be gradual and uniform in which case the longitudinal elements of the roll surface are straight lines from the middle to each end. Or the surface may be shaped so that the elements are curved lines, either uniformly so or variably so with the curvature increasing toward the ends. As here shown, the upper roll 27 has the longitudinal elements of its surface, as straight lines while the lower roll 28 is truly cylindrical, but these relations might be reversed with the upper roll cylindrical and the lower roll of varying diameter.

60 It is also preferable that one of the rolls 27, 28 have a surface which is somewhat yieldable so that as the rolls are moved closer together the extent of engagement of the cloth will be varied. As here shown the upper roll 27, represented as 65 being made of a suitable rubber composition, but it might be provided merely with a surface covering of such material or other material of yieldable nature.

As the strip passes the bar 20 and becomes 70 visible to the operator standing beyond the winder (not shown) in the neighborhood of the hand-wheel 47, he can readily determine whether or not any bowing is present in the cloth. If he finds that the cross threads are curved as at 75 B1 in Figure 1, and the cloth is moving in the

direction of the arrows, he turns hand-wheel 47 to raise shaft 48 and thereby depress the arms 41, 25 and 26. This forces the upper roll 27 toward the lower roll 28 and where the non-cylindrical surface of the upper roll firmly presses the cloth A which is between the rolls against the lower roll, that portion of the cloth will assume the speed of travel of the surface of roll 28. 5

With the filling threads bowed as at B1 in Figure 1, the variable speed device will be set so 10 that the roll 28 is traveling at a greater speed than the cloth. In consequence, as the cloth is gripped by the rolls the portion so gripped will be speeded up and travel forward faster than the edges of the strip. Because of the varying 15 diameter of the upper roll, the greatest pressure is exerted on the piece at its middle where the diameter of the upper roll is largest and less pressure will be exerted progressively towards the ends of the roll. This variation in pressure re- 20 results in variation in the speed imparted to the cloth by the rolls so that the middle portion of the piece is speeded up to the greatest extent while toward the ends of the rolls as the pressure between them lessens the cloth is permitted gradually to slip so that its speed approaches the speed of the edges. This leads to a complete 25 straightening of the bowing and restores the woof threads straight across the warp.

If the bowing is in the reverse direction, as at 30 B2 in Figure 1, the speed of the roll 28 will be adjusted to less than that of the cloth and as a result the middle portion of the strip will be most retarded with less retardation toward the ends of the rolls. Again the bowing will be eliminated. 35

It is evident that if the bowing is not too great, the necessary variation in speed to be imparted by the rolls can be controlled almost entirely by the hand-wheel 47, but if the bowing should be unusually large, then it is desirable to change the 40 speed of the rolls by means of the variable speed device 36. Such changes are readily made by the operator while the strip is continuing to travel and as a result the cloth is presented to the winder and wound up thereon with the bow- 45 ing eliminated.

While I have shown the upper roll 27 as a pressure roll it is to be understood that this roll might also be positively driven, in which event the lower roll could be a pressure roll or driven 50 as shown. Also, the lower roll might be arranged to be moved toward or from the upper roll, but I prefer the arrangement shown.

I claim:

1. Apparatus for eliminating bowing in a piece 55 of cloth comprising, in combination, feeding means engaging the edges of said piece and capable of positively moving each edge at a predetermined speed and means for simultaneously engaging the piece intermediate of its edges and 60 capable of positively moving said piece intermediate of its edges at a speed different from that of the said edges; the said piece being moved in its own plane by the said engaging means.

2. Apparatus for eliminating bowing in a piece 65 of cloth comprising, in combination, feeding means engaging the edges of said piece and capable of positively moving each edge at a predetermined speed and means for simultaneously engaging the piece intermediate of its edges and 70 capable of positively moving said piece intermediate of its edges at a speed different from that of the said edges; the said piece being moved in its own plane by the said engaging means so as to impart the greatest difference in speed to 75

that portion of the piece where the bowing is greatest and to impart less difference in speed from said portion toward the edges of the piece.

3. Apparatus for eliminating bowing in a piece 5 of cloth comprising, in combination, feeding means engaging the edges of said piece and capable of positively moving each edge at a predetermined speed and means for simultaneously feeding the piece intermediate of its edges at a speed different from that of the said edges; the 10 last said means comprising a pair of rolls engaging the piece intermediate of its said edges.

4. Apparatus for eliminating bowing in a piece 15 of cloth comprising, in combination, feeding means engaging the edges of said piece and capable of positively moving each edge at a predetermined speed and means for simultaneously 15 feeding the piece intermediate of its edges at a speed different from that of the said edges; the 20 last said means comprising a cylindrical roll and a non-cylindrical roll constructed and arranged to engage the piece intermediate of its said edges.

5. Apparatus for eliminating bowing in a piece 25 of cloth comprising, in combination, feeding means engaging the edges of said piece and capable of positively moving each edge at a predetermined speed and means for simultaneously feeding the piece intermediate of its edges at a speed different from that of the said edges; the 30 last said means comprising a cylindrical roll and a non-cylindrical roll constructed and arranged to engage the piece intermediate of its said edges; one of said rolls having a yieldable surface and there being means to control the relation of 35 said rolls to one another to vary the extent of engagement of the piece between them.

6. Apparatus for eliminating bowing in a piece 30 of cloth comprising, in combination, feeding means engaging the edges of said piece and ca-

pable of positively moving each edge at a predetermined speed and means for simultaneously feeding the piece intermediate of its edges at a speed different from that of the said edges; the 5 last said means including a cylindrical roll and a non-cylindrical roll having its greatest diameter substantially at the center line of said piece; one of said rolls having a yieldable surface and there being means for moving said rolls relatively to one another to engage the piece between them. 10

7. Apparatus for eliminating bowing in a piece 15 of cloth comprising, in combination, feeding means engaging the edges of said piece and capable of positively moving each edge at a predetermined speed and means for simultaneously 15 feeding the piece intermediate of its edges at a speed different from that of the said edges; the 20 last said means comprising a pair of rolls engaging the piece between them; and means for changing the speed of said rolls to vary the relative speed of said edges and the piece intermediate of its edges. 20

8. Apparatus for eliminating bowing in a piece 25 of cloth comprising, in combination, feeding means engaging the edges of said piece and capable of positively moving each edge at a predetermined speed and means for simultaneously feeding the piece intermediate of its edges at a speed different from that of the said edges; the 30 last said means comprising a cylindrical roll and a non-cylindrical roll constructed and arranged to engage the piece intermediate of its said edges; the non-cylindrical roll being made of yieldable material; and means for moving said non-cylindrical roll toward or from the other 35 roll to vary the extent of their engagement with the piece. 30

FRANK J. STEVENS.
